Springfield Photomount Company, Holyoke,
Mass., a corporation of Massachusetts

Application September 4, 1936, Serial No. 99,460

2 Claims. (Cl. 206—63)

This invention relates to improvements in portfolios and is directed more particularly to the provision of an improved portfolio of writing paper or the like and envelopes therefor.

5 It is one of the principal objects of this invention to provide a portfolio which is simple and easy to manufacture so as to be relatively inexpensive and which is of novel form so that a sheet or sheets of paper, as well as one or more envelopes, may be readily removed when desired. At the same time, the portfolio is constructed so as to be compact whereby it may be easily packed, shipped, and stored, and the portfolio is arranged to support the paper and envelopes for writing purposes.

10 It is one of the further objects of the invention to provide a portfolio which has hinged parts swingable between closed and open positions and arranged so that the articles are substantially protected while the portfolio is closed and so that the paper and envelopes are readily accessible when the portfolio is open. As a particular feature, the portfolio includes a plurality of sheets of paper removably supported in writing position 15 and a plurality of envelopes retained in a pocket member which is hingedly associated with the portfolio in such a way as to facilitate ready withdrawal of the envelopes.

15 Various other objects and advantages of the invention will become more apparent after a reading of the following description of the present preferred form thereof, and reference will be had in that description to the accompanying drawing wherein:

20 Fig. 1 is a perspective view of the portfolio of the invention in open position;

Fig. 2 is an elevational view showing the portfolio in closed position;

Fig. 3 is a partial plan view of the portfolio 25 in open position;

Fig. 4 is a sectional view on the line 4—4 of Fig. 3 with the parts in the relation shown in Fig. 5; and

Fig. 5 is a partial perspective view to explain 30 certain features of the invention.

Referring now to the drawing more in detail, the invention will be fully described.

In Fig. 1, there is shown what may be called the cover or supporting member of the portfolio 35 and this preferably comprises two parts 2 and 4 hinged together by a hinge, such as 6, between adjacent marginal edges as shown. Thus, the parts 2 and 4 are adapted to swing between an open position in substantially the same plane with one another as shown in Fig. 1 and a closed

position where the parts overlie one another as shown in Fig. 2.

The parts 2 and 4 are preferably formed of some relatively rigid material, such as heavy cardboard, wood, or the like, and are of substantially equal area. If desired, the parts may be covered with some suitable covering material, 21, such as cloth, heavy paper or the like, and this can be particularly formed as will later appear.

The inner surface of at least one side of the support is provided with pocket members and these are movable relative to the support. The members are adapted to receive a plurality of envelopes E or the like, while the inner surface of the other supporting member, such as 4, is arranged to have a plurality of sheets of writing paper or the like removably associated therewith.

Preferably, these sheets take the form of a pad P from which the sheets may be torn and having a cover or tab member removably held 20 in a suitable slit provided directly in the member 4 or in the covering material 21. In this way, when the supply of sheets is exhausted, the pad P may be removed and a new one inserted in its place.

This pocket member is hinged to the part 2 so as to be swingable between a lower position overlying the same as shown in Fig. 1 and an upper position as shown in Figs. 4 and 5. It will be appreciated that when the pocket and envelopes E are in the said lower positions, the portfolio may be folded into closed position so as to form the compact arrangement shown (see Fig. 2), while when raised to its upper position, the pocket permits ready withdrawal of the envelopes.

According to the preferred form of the invention, the pocket is formed in a particular way now to be described so that it has a cover flap and so that it may be completely removed from the portfolio, if desired.

In the form shown, the pocket-forming member is formed of foldable sheet material, such as stiffish paper, and there is a body part 20 having a cover flap 22 hinged to one marginal edge thereof, as by hinge 28, and a part 24 hinged to the 45 opposite marginal edge thereof, as by hinge 27. Hinged to opposite side edges of member 24, as by connecting parts 25, are retaining members 26.

The cover 21 is provided with spaced slits 14 50 and the sheet material is inserted therein so that the body 20 is disposed beneath the covering material which is between the slits. With this arrangement, a stack of envelopes E may be placed adjacent part 24 with members 26 adjacent the 55

opposite side of the stack and the lower marginal edge of the stack disposed next to the hinge 21. These last named parts thus form a pocket and both the pocket and its contents may be swung 5 relative to body part 20 as well as the part 2.

It will be seen that when the pocket and envelopes are swung down so as to overlie the inner surface of part 2, the cover flap 22 may be swung down to overlie the outside of the same, as shown. 10 If desired, some cooperative fastening means, such as the usual snap fastener, may be associated with flaps 24 and 22 so that these members are releasably held in closed position.

It is also to be noted that the whole pocket-forming member may be removed from beneath the covering material so that a separate package may be formed with the envelopes held between walls 20 and 24. This makes it possible for the manufacturer to produce these separate packages and distribute them as replacement fillers to the owners of the supporting member, just as may the pads P be sold separately for replacement purposes. It is desired to point out that the particular formation of the pocket is not as 25 significant as is the fact that it is hingedly associated with the support in such a way that it may move between a lower position and upper positions on an angle to the surface of the support.

30 Various changes and modifications may be made in the form of the invention without departing from the spirit and scope thereof and therefore I desire to be limited, if at all, by the appended claims rather than by the foregoing 35 description.

What I claim is:

1. As a new article of manufacture, a portfolio of the class described comprising in combination, a substantially flat support member, 40 covering material secured to and overlying a surface of said member, said covering material being provided with a pair of substantially parallel slits spaced apart a certain distance, and a lon-

5 gitudinal pocket-forming member of foldable material inserted into said slits so as to have an intermediate portion disposed between the support member and the portion of the covering material between the slits and end portions at opposite ends of the intermediate portion disposed above the covering material, the said pocket-forming member being folded along lines extending between the said intermediate and end portions whereby the end portions may swing relative to the surface of said support member. 10

2. As a new article of manufacture, a portfolio of the class described comprising in combination, a substantially flat support including a pair of members hinged together for swinging between an open position in substantially the same plane with one another and a closed position overlying one another, covering material folded about at least one of said flat members and provided with a pair of substantially parallel 20 slits spaced apart a certain distance, and a removable member of foldable sheet material inserted into said slits with an intermediate portion disposed between the said flat member and the portion of the covering material between the 25 slits and end portions at opposite ends of the intermediate portion disposed above the covering material, the said end portions being connected to said intermediate portion by hinges whereby the end portions may swing relative to the 30 surface of said one flat member, and one of said end portions being provided with side flaps which extend inwardly from opposite sides thereof and co-operate therewith to form a pocket member, all adapted and arranged whereby said pocket 35 member may be swung downwardly on the hinge connecting said one end portion and said intermediate portion to overlie said portion of the covering material between said slits and whereby said other end portion may then be swung downwardly on the other hinge to overlie the pocket member. 40

OSCAR W. JOLLY.
